(57) CLAIM

The ornamental design for playground equipment, as shown and described.

DESCRIPTION

FIG. 1 is a top perspective view of playground equipment showing our new design;

FIG. 2 is a right side view of the playground equipment shown in FIG. 1, with the left side view being a mirror image thereof;

FIG. 3 is a top view of the playground equipment shown in FIG. 1;

FIG. 4 is a rear view of the playground equipment shown in FIG. 1;

FIG. 5 is a front view of the playground equipment shown in FIG. 1; and,

FIG. 6 is a bottom view of the playground equipment shown in FIG. 1.

The broken lines shown in the figures are for illustrative purposes only and form no part of the claimed design.
